AIR CONDITIONED GARMENT

John Hellmann, Ernest L. Keyes, and Joseph A. Petrone, Pittsburgh, Pa.

Application October 17, 1938, Serial No. 235,386

2 Claims. (CL 128—144)

This invention relates to air conditioned garments and more particularly to garments intended to be used by furnace tenders, firemen or others who operate close to heat or fire.

One of the objects of the present invention is to provide a garment of fire-proof and semi-pervious fabric which may be fed with cool and fresh air so as to entirely surround the user with an envelope of cool and fresh air within said garment.

Another object of the invention is to provide a garment with means to feed and distribute a stream of clean and cool air to the various portions of the body of the wearer.

Still another object of the invention is to provide a garment of semi-airtight fabric with a metallic distributor by means of which fresh and cool air may be fed to the wearer for breathing and cooling purposes.

A further object of the invention is to provide a garment with a metallic distributor which is made in two parts and hingedly connected together.

Another object of the invention is to provide a device which may be readily and comfortably worn by a person in discharge of his duty, and which will not hamper his movements in the least.

Other objects of the invention are to provide a device of the class set forth which is simple in its construction and arrangements, durable and efficient in its use, readily worn, and inexpensive to manufacture.

To the accomplishment of these and such other objects as may hereafter appear the invention consists of the novel construction, combination and arrangement of parts herein specifically described and illustrated in the accompanying drawing, wherein is shown an embodiment of the invention, but it is to be understood that changes, variations and modifications may be resorted to which come within the scope of the claims hereunto appended.

In the drawing wherein like numerals of reference designate corresponding parts throughout the several views.

Figure 1 is a front view of the complete garment spread open to show the air distributor secured to the interior of the garment.

Figure 2 represents the garment as it appears when worn by an operator.

Figure 3 is a rear view of Figure 1 showing how part of the upper portion of the air distributor protrudes through the garment; it also shows the air inlet hose by means of which fresh air is supplied to the user.

Figure 4 is an enlarged front view of the

hingedly connected upper and lower portions of the air distributor.

Figure 5 is a side view of Figure 4.

Figure 6 is a sectional enlarged view along line 6—6 in Figure 5 showing how the upper and lower portions of the air distributor are hinged together.

Referring to the drawing, and particularly to Figure 1, there is shown a front view of an air conditioned garment 10, in accordance with our invention, preferably made of fire-proof fabric, such as for instance asbestos cloth, or any other suitable material. This garment is arranged to be inflated with air so as to completely surround the user, but it is desirable that the fabric be sufficiently porous to permit a certain quantity to escape through the fabric.

Fresh air is forced through a flexible hose 11 by means of a fan (not shown) or any other suitable device and through a distributor 12, which is preferably made in two parts, the lower portion 13 and the upper portion 14, both produced of light weight material such as aluminum or any other metal suitable for the purpose.

The aforesaid garment 10 is preferably made in the form of a union suit (one piece) provided at the front with a vertical seam 15 which may be closed and opened by means of a mechanical lacing 16, commonly known as a "zipper".

The hood 17, which slips over a steel helmet 18, usually worn for head protection, extends downwardly, as indicated by the numeral 19 and is secured at the back of the garment to the shoulder end 20 but the front is removably attached to the garment by means of the mechanical lacings 35 21 and 22.

In front of the eyes of the wearer is a window 23 of mica or other fire resisting material through which the operator may see. The gloves 24, 25 as well as the shoes 26, 27 are preferably made in one piece with the garment.

Secured to the inside of the back part of the garment, in a manner as shown in Figure 1, is the air distributor 12 by means of which fresh air is distributed to the various portions of the body, and referring now to Figures 4, 5 and 6 the said air distributor 12 consists of a hollow lower portion 13, curved inwardly, so as to conform to approximately the shape of the back of the waist of the user. Substantially midway along the upper edge 28 of said lower portion 13 is a vertically disposed conduit 29, preferably formed integrally with said lower portion 13, over which loosely slips the depending conduit 30 of the hollow upper portion 14 of distributor 12.

5 The aforesaid depending conduit 29 branches out at the top into a pair of oppositely directed conduits 31 and 32, each of which has a slightly reduced tapered connecting sleeve 33 and 34 respectively adapted to connect thereon a short piece of flexible discharge hose 35 and 36 respectively. At the meeting joint 37 of said conduits 31 and 32 is an upright nozzle outlet 38 which is intended to supply a stream of fresh air to the head of the body of the user, whereas the terminals of said flexible hose 35 and 36 are intended to furnish a stream of air to the arms 39 and 40.

10 In order to permit stooping or bending the body of the operator forward, the uppermost end 15 of conduit 29 of lower portion 13 of said distributor 12 is inserted into the depending conduit 38 of upper portion 14 of distributor 12 and hingedly connected thereto by means of oppositely disposed pins or screws 41 and 42 as 20 shown in Figure 6.

15 As best shown in Figures 4 and 5 the lower portion 13 of distributor 12 is provided with a pair of oppositely directed outlets 43 and 44 which are bent inwardly so as to direct the 25 flow of the air to the front of the waist of the operator.

20 A pair of oppositely directed outlets 45 and 46 at the bottom of said lower portion 13 of distributor 12 are directed downwardly and intended 30 to supply fresh air to the legs of the operator.

25 Fresh air is conveyed to the operator from a fan (not shown) or a tank containing air (not shown) to the distributor 12 by means of said flexible hose 11 which is properly attached to a flanged sleeve 47 which penetrates through the back of the garment in a manner as shown in Figures 3 and 5 of the drawing.

30 As will be best seen in Figure 3, the major part 35 of the upper portion 14 of distributor 12 is fastened at the outside of the back part of the garment but the flexible hoses 35 and 36 are introduced into the interior of the sleeves 50 and 51 through slits 48 and 49, respectively, of 40 the garment. The nozzle outlet 38 is introduced 45 into the interior of the hood 17 through a slit 52 as shown in Figure 3.

45 The reason for attaching the upper portion 14 of the distributor 12 to the outside of the garment is to avoid undesirable pressure of the metallic distributor against the back of the operator.

50 It will be seen, that the improved garment is 55 so arranged, that the head, arms, chest and the legs receive a continuous stream of fresh air

acting as a cooling medium when the operator has to work in a hot place.

5 In using this device the fresh air enters from a source of supply (not shown) through said flexible hose 11 and passes out through the outlets 35, 36, 38, 43, 44, 45 and 46.

10 It will be obvious that it is not necessary to provide air exhaust ports for this device for the reason that the fabric out of which the garment is to be made is sufficiently porous to permit a certain volume of air to escape out of the garment at all times without impairing the efficiency 15 of the device as a fresh air supply.

15 From the foregoing description, taken in connection with the drawing, it will be seen that our invention provides a garment of the character set forth which is simple in construction and designed to carry out the objects of the invention in a reliable and efficient manner. It will, of course, be understood that while the construction disclosed is preferred, changes for and within 20 the scope of the appended claims may be made without departing from the spirit of or sacrificing any of the advantages of the invention.

25 We claim:

1. In a device of the class described, the combination of a garment in the form of a union suit including a separable hood adapted to completely inclose the body of the wearer; an air supply and means to distribute the air from said air supply within said garment, said distributing means comprising a two piece hollow body hingedly connected together and provided with a plurality of differently directed air outlets, one 35 piece of said hollow body secured to the inner back of said garment and the other piece secured to the outer back of said garment.

2. In a device of the class described, the combination of a garment in the form of a union suit including a separable hood adapted to completely inclose the body of the wearer; an air supply and means to distribute the air from said air supply within said garment, said distributing means comprising a two piece hollow body 40 hingedly connected together and provided with a plurality of differently directed air outlets, one piece of said hollow body secured to the inner back of said garment, the other piece secured to the outer back of said garment, all of said plurality of air outlets of said air distributing means 45 terminating within the interior of said garment.

JOHN HELLMANN.
